HAIR CURLER

Yolanda I. Licastro, New York, N. Y.

Application October 6, 1948, Serial No. 53,110

6 Claims. (Cl. 132—43)

1

The present invention relates to hair curlers and has for its object the provision of a new and improved hair curler, which is comparatively inexpensive to manufacture, which can be easily and quickly applied to the hair by simple manipulation, even by the wearer, which forms a neat attractive ringlet when applied, which when applied occupies a minimum of space and forms a compact unit with the hair curl, so that it does not become too obtrusive and does not present an unsightly appearance in applied condition, which is comfortable to wear even when the wearer's head is resting on a pillow, which requires no wires or bobby pins, and which has a minimum of metal or rigid pads, arranged, if present, so that they cannot damage the hair, injure the scalp or in any way produce discomfort.

Various other objects of the invention will be apparent from the following particular description and from an inspection of the accompanying drawings, in which:

Fig. 1 is the front elevation of a hair curler embodying the present invention;

Fig. 2 is a rear elevation of the hair curler;

Fig. 3 is a transverse section of the hair curler taken along the lines 3—3 of Fig. 1, but shown on a larger scale with the thicknesses of the different fabric layers exaggerated;

Fig. 4 is a transverse section of the hair curler taken on lines 4—4 of Fig. 1, but shown on a larger scale with the thicknesses of the different fabric layers exaggerated.

Fig. 5 is a plan view showing an initial step in the manufacture and assembling of the hair curler;

Fig. 6 is a plan view showing a subsequent step in the manufacture and assembling of the hair curler;

Fig. 7 is a perspective showing the hair curler about to be applied to a strand of hair for curling;

Fig. 8 is a perspective showing the hair curler fully applied to a strand of hair for curling and locked thereon; and

Fig. 9 is a side view of a portion of a hook which may be used to thread a strand of hair through a slit in the curler.

Referring to Figs. 1 to 4 of the drawings, the hair curler of the present invention comprises a folded flexible sheet of textile fabric 10, which when unfolded is of generally rectangular shape and specifically of substantially square shape. This sheet 10 may have straight outer edges or may have scalloped or otherwise finished outer edges 11, as shown, for ornamentation and/or

2

to prevent ravelling, and is doubly folded along the edge 12 and then doubly folded again along the double layer edge 13, to form an oblong rectangular curler, as shown in Figs. 1 and 2, with 5 two overlapping double layer sections 14 and 15 and a pocket 16 defined in one of said sections 15 between said fold edges 12 and 13.

Near the fold edge 13 and extending therealong midway between the ends of the curler is 10 a slit 18 of the buttonhole type having its edges finished by conventional buttonhole stitching.

In order to provide a core around which a strand of hair may be neatly curled to form a ringlet, the pocket 16 of the curler section 15 is 15 stuffed or filled with a suitable material to distract it, and more specifically with a wad or pad roll 20. This wad or pad roll 20 comprises desirably a small compact mass 21 of any soft or flexible substance such as cotton or lint, retained in 20 a light fabric covering 22, such a gauze, stitched loosely at the ends to close said ends. One or more cords 23 may be located in the center of the cotton mass 21 to give body to the roll mass 21 and to prevent said mass from flattening out.

25 The wad or pad roll 20 may be of the form well-known to dressmakers and used as stuffings or packings for trimmings, decorations, etc., and is frictionally retained snugly in the pocket 16 of the curler section 15 against endwise movement, midway of the ends of the curler. This pad roll 20 is substantially shorter than the length of the folded sheet 10, so that the end portions of said sheet for substantial lengths extend beyond the corresponding ends of said pad roll and may, therefore, be overlapped with 30 minimum of interference from said pad roll in the application of the hair curler to the hair.

In order to fasten the ends of the curler together on the strand of hair after it has been wound around said curler, the ends of the curler have secured thereto fasteners 25 and 26. These 40 fasteners 25 and 26 are desirably of the dress snap type and comprise a female element 25 stitched to one end of the curler on one side thereof and a male element 26 stitched to the other end of the curler on its other side. The stitching of these fastener elements 25 and 26 45 serves not only to attach these elements to the curler but also to secure together the overlapping curler sections 14 and 15.

The curler may be manufactured and assembled in an easy and inexpensive manner. In the process of manufacture and assembling, the textile sheet blank 10a, while imperforate, is laid out 50 flat on a table, as shown in Fig. 5, and the pad 55 flat on a table, as shown in Fig. 5, and the pad

roll 20 is placed in proper position on said sheet. The blank 10a is then doubly folded over the pad roll 20 and the two overlapping panels of said blank cut and buttonhole stitched on one side of the pad roll 20 to form the slit 18 and the sheet 10, as shown in Fig. 6. The buttonhole stitching serves not only to finish the edges of the slit 18 but also to fasten the two overlapping panels of the sheet 10 together, as shown in Fig. 6. The assembly shown in Fig. 6 is then again doubly folded along a longitudinal line substantially coincident with the longitudinal center line of the slit 18 to form the overlapping curler sections 14 and 15 and the snap fastener elements 25 and 26 are stitched in position, as shown in Figs. 1 and 2, to attach said elements to the curler and to secure these overlapping sections together near their ends.

In applying the curler to a strand of hair A, this strand after being combed out is threaded between the curler sections 14 and 15 and through the slit 18 and the ends of said strand are curled around the padded curler section 15, as shown in Fig. 7. The neat threading of the hair strand through the slit 18 can be effected very easily and neatly, as for example, by spreading the two curler sections 14 and 15 apart near the center and then pushing the strand of hair with a finger through the slit 18.

If desired, the threading of the hair strand through the curler may be accomplished simply and without disarranging the hairs of said strand, by means of a hook 27 shown in Fig. 9. Threading by means of this hook 27 is accomplished by inserting the hook through the slit 18 of the curler and in between the curler sections 14 and 15 and catching said hair strand with said hook. With the hair strand so engaged, the hook 27 is withdrawn from between the curler sections 14 and 15 and through the slit 18, causing the hair strand to be passed neatly through said slit.

With the strand of hair threaded through the slit 18, any hairs which are too short to pass through said slit are nevertheless retained neatly between the overlapping curler sections 14 and 15 initially before the turning of the curler for hair wrapping is begun.

After the curler has been set up on the outer end of the strand of hair, as shown in Fig. 7, the curler is turned about its longitudinal axis to cause said strand to wrap itself first on the padded curler section 15 for the first convolution and then around both curler sections 14 and 15 combined for subsequent convolutions, until a sufficient length of said strand has been wrapped. The curler is then looped, the two ends of the curler are brought together in overlapping relationship and the two fastener elements 25 and 26 are snapped together, as shown in Fig. 8. As many curlers are so used and applied for respective hair strands as are required.

After the curler has been retained on the stand of hair for sufficient time to cause the resulting curl or ringlet to become set, the curler may be very easily removed by simply separating the fastener element 25 and 26 and pulling the curler off the strand. The curler can then be used over and over again indefinitely.

If desired, the curler sheet 10 may be made of textile, which is waterproof or which has been rendered waterproof by treatment. This is especially suitable where it is desired to use the curlers with damp hair. If desired, the curler sheet may be of suitable plastic material, such as Koro-seal, Pliofilm, etc.

The curler sheet 10 may be of any color desired and may, for example, be of a color to match the hair, so that the curler will not be too obtrusive. Since the curler wraps itself around the strand of hair very compactly, it attracts little attention.

The curler is free from wires, bobby pins, and other metallic or rigid parts which may dig into the scalp or injure the hair and which make it uncomfortable to lie down with the hair set up in curlers. Whatever metal parts are present in the form of fastener members 25 and 26, are too small and are too well cushioned to produce any discomfort or injury to the hair.

15 While the invention has been described with particular reference to a specific embodiment, it is to be understood that it is not to be limited thereto, but is to be construed broadly and restricted solely by the scope of the appended 20 claims.

What is claimed is:

1. A hair curler comprising a single flexible fabric sheet doubly folded once and then doubly folded again to define two oblong substantially 25 rectangular double layer sections in overlapping relation, the fold edge between said sections having adjacent thereto and extending therealong a slit through which a strand of hair to be curled is adapted to be threaded, one of said sections 30 being filled between the two layers thereof along said slit and on one side thereof to form a core for the hair strand when wrapped around said curler, and fastening elements secured to the ends of said sections and adapted to be releasably 35 interlocked when the ends of said sections are brought together in overlapping relationship.

2. A hair curler as described in claim 1, the edges of said slit being buttonhole stitched, to finish said edges and to fasten the two sheet 40 panels formed by the first folding operation together.

3. A hair curler as described in claim 1, said fastening elements being secured to said sections by means, which fastens the overlapping sections 45 together.

4. A hair curler comprising a single flexible sheet folded once and then folded again to define a pair of overlapping sections, and to define a pocket in one of said sections, and filling in said 50 pocket serving as a core for the hair strand when wrapped around said curler, said curler having a slit between said sections through which a strand of hair to be curled is adapted to be threaded, said sections being adapted to be turned 55 to cause the hair strand to wrap itself first upon one of said sections and then upon both sections together, and means for securing said sections on the wrapped hair strand against unwinding action.

60 5. A hair curler as described in claim 4, said filling being in the form of a pad roll made entirely of soft flexible material, said pad roll being substantially shorter than the length of the sections, so that the end portions of said sections

65 extend for substantial lengths beyond the corresponding ends of said roll and may be folded into overlapping relationship with minimum of interference from said pad roll in the application of the hair curler to the hair, the end portions of said sections being adapted to be secured together in overlapping relationship by said securing means.

70 6. A hair curler as described in claim 4, said filling being in the form of a pad roll made entirely of soft flexible material, said pad roll being 75

substantially shorter than the length of the sections, so that the end portions of said sections extend for substantial lengths beyond the corresponding ends of said roll and may be folded into overlapping relationship with minimum of interference from said pad roll in the application of the hair curler to the hair, said securing means comprising snap fasteners attached to the end portions of said sections in a manner to secure the superimposed layers of the sheet together at said end portions and serving when secured together to hold said end portions in overlapping relationship.
